UNITED STATES PATENT OFFICE.

BERTUS A. LAKE, OF BIG PRAIRIE, OHIO.

SELF-HEATING SADIRON.

Application filed June 4, 1926. Serial No. 112,803.

The invention relates to self-heating sad-irons of the type set forth in my prior Patent No. 1,558,097, dated October 20, 1925, and more particular to the construction of the 5 combustion chamber and flues therefor; and the objects of the invention are to provide for self-heating sad irons improved combustion chambers and flues therefor, which are simple and inexpensive to manufacture 10 and durable and efficient in use, and including improved means for delivering air to the combustion chamber, for creating a more efficient combustion of the fuel at the burner, for transmitting the heat of the burning flame 15 to the sad-iron base and the ironing surface thereof, and for rapidly and thoroughly eliminating the products of combustion from the combustion chamber.

These objects are attained by the preferred 20 construction and arrangement hereinafter described and illustrated in the accompanying drawings forming part hereof, in which—

Figure 1 is a side elevation of a sad-iron embodying the present improvements;

Fig. 2, a fragmentary vertical axial cross section thereof; and

Fig. 3, a fragmentary transverse cross-section thereof, as on lines 3—3, Figs. 1 and 2.

Similar numerals refer to similar parts 30 throughout the drawings.

A preferred form of the improved self-heating sad iron is indicated generally at 1, and includes a base 2 having the usual bottom ironing surface 3, a middle section 4 and 35 a double cover 5, removably associated with each other as by means of pins 6. Threaded lower ends 7 of reduced diameters, are provided on the pins 6, and pass through apertures 8 in a preferably horizontal web 9 extending inwardly substantially midway intermediate the upper and lower edges of the middle section 4, and are screwed into threaded apertures 10 in upwardly extending medial lugs 11 of the iron base 2. The body section of the pins 6 thus form bolt heads for securely clamping the iron middle section to the iron base section. The pins 6 are located one on each side of the longitudinal axis of the iron and extend upwardly through apertures 12 in the double cover 5, and are provided at their upper ends with annular grooves 13 for selective cooperation with cam edges 14 of a locking lever 15 pivotally secured to the double cover as at 16.

The double cover 5 includes a bottom plate 17 and a top plate 18 secured to each other

as by screws 19 and being provided with a heat resisting sheet 20, preferably of asbestos, between the plates for retarding the passage of heat from the bottom plate to the top plate. 60

The bottom plate may be provided with a plurality of outwardly directed grooves 21 communicating with apertures 22 in the plate for carrying hot gases through the bottom plate and deflecting the same by means of 65 the asbestos sheet outwardly from the iron through the grooves 21.

Screws 19 may likewise secure to the top plate 18 the handle 23 for the iron.

The iron base forms the bottom wall, the 70 middle section forms the side walls, and the cover forms the top wall of the improved combustion chamber indicated generally at 24, in which is located the burner 25 of a usual and well known construction, the burner being 75 attached to the generator 26 which is connected by means of the feed pipe 27 to the fuel tank 28.

The base 2 of the iron is provided with an upper surface 29 preferably parallel with the 80 lower ironing surface 3, and with upwardly extending end lugs 30 and 31 whose upper surfaces 30' and 31' are above the level of the surface 29, and upon which upwardly extending lugs middle section 4 is supported so 85 that its lower edge 32 is elevated above the surface to form preferably horizontal air inlet slots 33 on each side of the iron.

The base 2 is also provided with a baffle wall 34 extending upward from the surface 29 90 substantially midway between the outer edges of the base and the longitudinal axis of the iron and forming a centrally located combustion bowl 35, the upper edge 36 of the baffle wall being preferably located a substantial distance above the lower edge 32 of the middle section and may be midway between the edge 32 and the lower surface of the web 9.

A longitudinal central aperture 37 preferably somewhat less in area than the bowl 35, is provided for the web 9, the web being located intermediate the lower edge 32 of the middle section and the upper edge 38, thereby forming a lower combustion compartment 24^a communicating with an upper exhaust compartment 24^b for the combustion chamber.

The cover 5 is supported slightly above the upper edge 38 of the middle section and the 110 edge 38 is preferably provided with a plurality of spaced notches 39 for providing exit

flues for the products of combustion in the combustion chamber.

The burner 25 is preferably provided with downwardly directed apertures 25' and 25" 5 for admitting fuel such as gasoline vapor to the combustion chamber.

In use the burner is lighted in the usual manner and the downwardly directed flame F heats the bowl 35 and the interior of the combustion chamber, thereby drawing air A 10 into the chamber through the slots 33. The outer surface of the vertically extending baffle wall 34 directs the incoming air upward against the lower surface of the web 9, 15 which in turn deflects the air downward into the combustion bowl for providing sufficient air for the purpose of completely burning the fuel. The wall 34 also acts as a heat collector for the base 2 since the burning fuel is 20 directed not only against the upper surface 29 of the bowl, but also against the inner surfaces of the wall 34.

The products of combustion pass upward through the aperture 37 and out through the 25 notches 39 in the upper edge of the middle section. Portions of the products of combustion may also pass up through the apertures 22 in the plate 17 and out through the 30 grooves 21.

By means of the foregoing construction and arrangement a highly efficient combustion of the fuel in the combustion chamber is attained, and a satisfactory quantity of the heat thus generated is transferred through 35 the wall 34 and the upper surface 29 to the base 2 and its ironing surface 3.

The provision of the notches 39 in the upper edge of the middle section enables not

only an efficient, but also a rapid combustion of fuel, since the flue draft area thus provided 40 is adequate for drawing sufficient quantities of the air through the combustion chambers for carrying on rapid combustion.

Moreover the provision of the flue notches 45 protects the cover from a considerable quantity of heated gases which would otherwise pass up through the apertures 22 and out the notches 21, thereby maintaining the handle 23 at a comfortable temperature for convenient 50 operation.

I claim:

A self heating sad iron including a base forming the bottom wall, a middle section forming the side walls, and a cover forming the top wall of an internal combustion chamber for the iron, side walls extending upwardly from the base and spaced substantially midway between the outer edges of the base and the longitudinal axis of the iron and extending upwardly a substantial distance 60 above the lower edge of the middle section and forming a combustion bowl and air baffle in the combustion chamber, a deflector web extending horizontally inwardly from the middle section walls substantially midway intermediate the upper and lower edges thereof and dividing the combustion chamber into a combustion compartment and an exhaust compartment, and there being an air inlet 65 between the base and the middle section for admitting air to the combustion chamber, and there being an exhaust outlet for the combustion chamber.

In testimony that I claim the above, I have hereunto subscribed my name.

BERTUS A. LAKE.
